GARMENT HANGER

John E. Whitman, Bremerton, Wash.

Application June 6, 1945, Serial No. 597,743

7 Claims. (Cl. 223—91)

1

The present invention relates to a garment hanger suitable for supporting the upper and lower portion of a man's or woman's suit.

While the hanger of my invention is or may be provided with the upper curved bow for receiving a coat, and a lower horizontal bar over which a skirt or pair of trousers may be hung in the usual way, there are special means provided, associated with the horizontal bar, for suspending a skirt by the waist band or a pair of trousers by the cuff, so that in either case the lower garment will hang straight downwardly, without being bent about and hung over the bar by its middle portion. The invention is primarily concerned with the manner in which two separate and independently shiftable garment engaging and suspending members may be supported upon and adjusted lengthwise of the bar, and may be held in operative position, as thus adjusted, so that they will not slide inwardly or together, and so that they will not be separated from the bar during the act of engaging the garment with or disengaging it from the garment suspending members.

The objects of the invention having been generally indicated above, these objects and others will appear more clearly as the description progresses.

In the accompanying drawings the invention has been shown in a presently preferred simple form, although it will be obvious, with better understanding of the invention, how the various forms may be modified without departing from the spirit of the invention.

Figure 1 is an elevation of the complete hanger, showing how a pleated skirt may be supported therefrom by the waistband.

Figure 2 is a cross-section through the horizontal bar of the hanger, showing the manner in which one of the garment suspending members cooperates therewith.

Figure 3 is a transverse section, substantially on the line 3—3 of Figure 2, the horizontal bar, however, being shown in plan.

The garment hanger may be made of any suitable material, and while metal may be used, it may also be made of a plastic material, and is so indicated. Its upper portion is or may be of any suitable or usual shape and construction, including, for example, the upper bow 1 shaped to support a coat, and a hook 2 by which the hanger as a whole may be supported from a suitable bar or like support.

The hanger comprises also the usual horizontal bar 3 connecting the outer ends of the bow 1, but in this instance the bar 3 is of a special construc-

2

tion. Preferably it is of inverted U-shape in cross-section, as is best seen in Figure 2, thus having two substantially upright faces. One such face would be sufficient for the purpose which will appear later, but conveniently both faces are flat and upright. The material of which the bar is constructed, whether plastic or metal or other suitable material, is sufficiently resilient that the lower edges of the flat faces may approach one another, as is indicated by the dash lines in Figure 2. When the force urging them together is removed, they will spring outwardly. Preferably also, one such face, at least, is formed with a series of spaced vertical grooves 4, or similar pattern means, engageable with complementary pattern means on the members now to be described.

Two members, designated in general by the numeral 5, are provided for use with each bar 3. They are of inverted U-shape to straddle and depend below the bar, and have inner faces complementary to the faces of the bar, and of appreciable extent lengthwise of the bar, so that each member 5 will be stable, and will not tend to rock either lengthwise of the bar or to rotate about the bar. Each such member 5 is provided with a vertical rib 6 on an inner face, or with other pattern means complementary to the pattern means or groove 4 of the bar 3. The interengagement of the rib 6 and a groove 4 further stabilizes the U-shaped member 5, and prevents shifting of the member 5 lengthwise of the bar, particularly when there is a tendency to pull the member 5 inwardly as the garment is stretched in the direction of the length of the bar 3, in attaching it. It will be evident, of course, that the outstanding rib 6 might be provided on the bar 3, and the complementary groove might be formed in the member 5.

Various forms of garment engaging and suspending means may be associated with the members 5, and I do not desire to be restricted in this respect, in so far as the general features of the invention are concerned. However, one particular form of garment engaging and suspending means is preferable, and the means for engaging the member 5 with and holding it to the bar 3 is particularly desirable or necessary in conjunction with the garment suspending means shown. These garment suspending means comprise an eccentric dog or disc 7 journaled at 8 at the lower end of one of the legs of the U-shaped member 5, the periphery of which, in certain positions, at least, is gravity-urged against the opposite leg 10 of the member 5, to dog and hold a garment, such as 9, which has been inserted between them. The garment is inserted by upward movement of its edge,

for instance the waist band, between the dog 7 and the face 10 at the lower end of the opposite leg of the member 5. The dog 7 yields to permit such insertion, but falls back by gravity to grip the garment when the hold thereon is released. Its face may be roughened, for better gripping. A limit stop 11 on the disc 7 may engage the member 5 to prevent the disc 7 from falling back away from the face 10.

As is evident, the insertion of the garment into a garment gripping device such as has just been described, or the removal of a garment therefrom, will produce some tendency to upward movement of the member 5, relative to the bar 3. To resist this movement I provide an inwardly directed locking dog 12, which may be at the lower end of the rib 6, or otherwise located, but so disposed that when the member 5 is properly seated upon the bar 3 the dog 12 will engage beneath the lower edge of a side face of the bar 3. It is permitted thus to engage by the resilience of the faces of the bar, in a manner which is clear from inspection of Figure 2. The member 5 is preferably so formed and reinforced that it is but slightly resilient, although to make the member 5 resilient, instead of the bar 3, or to make both equally resilient, would be in effect a mere reversal or extension of the form already described.

As a matter of fact, the member 5 has sufficient resilience that it tends to spread slightly when the dog 7 is pressed tight, and this resilience assists in holding the dog in clamping position. The locking dog 12 holds the member 5 when some appreciable upward force is employed to disengage suspended garments.

The two members 5 may be disengaged from and then adjusted lengthwise of the bar, the dog 12 being disengaged to permit their shifting by pressing inwardly upon the lower edges of the side faces of the bar 3. When they are adjusted to the correct spacing, they are pressed downwardly, relative to the bar, to engage the rib 6 with a groove 4 and to snap the dog 12 beneath the edge of the bar. Thus engaged they may not move relatively, lengthwise of the bar, about the bar, nor be canted relatively to the bar, nor can they be readily moved upwardly with respect to the bar. Now the garment is engaged by inserting its edge, such as the waist band or the cuffs of a pair of trousers, upwardly between the disc 7 and face 10, engaging it thus with each of the suspending members 5. When the disc 7 is turned inwardly against the garment and the opposite face 10, the garment is clamped in suspended position, and the hanger may be hung up, or a coat may be draped upon the upper bow 1. Release of the thus suspended garment requires only that the garment be lifted slightly relative to the hanger as a whole, to rotate the clamping dogs 7 from their clamping position.

I claim as my invention:

1. A garment hanger including a horizontal bar having at least one flat side disposed in an upright plane, a pair of inverted U-shaped members each having means to engage and suspend a garment, and of a size and shape to straddle said bar and to lie closely against the flat side thereof, to prevent rotation of the garment-engaging members about the bar, and means interengageable between the bar and each of said members to positively retain said members against sliding lengthwise of said bar.

2. A garment hanger including a horizontal

bar, a pair of inverted separable U-shaped members each having means to engage and suspend a garment, and of a size and shape to straddle and closely embrace said bar, and complementary rib and groove means interengageable directly between the bar and each of said members to positively retain the members in their spaced-apart positions along the bar against pull lengthwise of the bar.

3. A garment hanger including a horizontal bar having opposite flat faces disposed in upright planes, a pair of inverted U-shaped members each having means to engage and support a garment, and having flat inner faces generally complementary to those of the bar, which said members straddle, the bar and said U-shaped members being relatively yieldable, transversely of the bar, to increase the relative gripping effect when the U-shaped members are seated upon the bar.

4. A garment hanger including a horizontal bar having opposite flat faces disposed in upright planes, a pair of inverted U-shaped members each having means to engage and support a garment, and having flat inner faces generally complementary to those of the bar, which said members straddle, the bar and said U-shaped members being relatively yieldable, transversely of the bar, to increase the relative gripping effect when the U-shaped members are seated upon the bar, and an inwardly directed dog on each U-shaped member, positioned to snap under the lower edge of the bar, by the relative resilience of the member and bar, and thus to restrain relative vertical movement of the two.

5. A garment hanger including a horizontal bar having at least one flat, generally upright face, with vertical grooves spaced along such face, a pair of separable inverted U-shaped members each having means to engage and suspend a garment, of a size and shape to straddle and closely embrace said bar, and each having a flat face complementary to the bar's flat face, a rib outstanding from such flat face of each member, complementary to the several grooves of the bar, and an inwardly directed dog upon each member, in position to engage beneath the lower edge of the bar when the member is snugly seated upon the bar, to resist upward disengagement of such member from the bar.

6. A garment hanger including a horizontal bar of inverted U-shaped section, and of somewhat resilient material, permitting limited approach of the opposite faces of the bar, a pair of separable members of inverted U-shape, having inner faces complementary to and adapted to seat upon the corresponding faces of the bar, means interengaged between the respective members and the bar, when thus seated at any one of a plurality of positions lengthwise of the bar, to prevent shifting of the members lengthwise of the bar, a dog inwardly directed from each member, and engageable beneath the bar's lower edge by the bar's resilience, when the member is seated upon the bar, to prevent movement of such member vertically relative to the bar and means carried by each member to engage and suspend a garment.

7. A garment hanger comprising a horizontal bar, generally of inverted U-shape in cross-section, and of material sufficiently resilient to permit limited approach of the lower edges of the two faces, a member of appreciable width, and of complementary U-shape, adapted to straddle

said bar and to extend therebelow, an eccentric disc journaled in one leg of said member, below the bar, and rotatable into clamping engagement with the opposite leg, when a garment has been received therebetween by upward entering movement of the garment, and an inwardly directed dog on said member, positioned to engage beneath the lower edge of one face of the bar by reason of the latter's resilience, and to prevent separation of said member from the bar by upward movement of the garment.
